CLAIM

The ornamental design for a multiply interconnectable environmentally interactive character simulation module, as shown and described herein.

DESCRIPTION

FIG. 1 illustrates a perspective view of a multiply interconnectable environmentally interactive character simulation module showing the front, left and top sides; and,

FIG. 2 illustrates a front view of the multiply interconnectable environmentally interactive character simulation module of FIG. 1.

The broken lines shown in FIGS. 1 and 2 are for illustrative purposes only and form no part of the claimed design.
